UNITED STATES PATENT OFFICE.

GEORGE H. SHATTUCK, OF TUMWATER, WASHINGTON.

GATE.

1,276,424.

Specification of Letters Patent. Patented Aug. 20, 1918.

Application filed April 3, 1917. Serial No. 159,504.

To all whom it may concern:

Be it known that I, GEORGE H. SHATTUCK, a citizen of the United States, residing at Tumwater, in the county of Thurston and 5 State of Washington, have invented certain useful Improvements in Gates, of which the following is a specification, reference being had therein to the accompanying drawing.

The invention relates to gates, and more 10 particularly to the class of vertically swinging balanced gates for roadways.

The primary object of the invention is the provision of a gate of this character wherein the same can be opened and closed from 15 either side thereof by an operator within a vehicle, thereby eliminating the necessity of leaving the vehicle for the opening or closing of the gate.

Another object of the invention is the 20 provision of a gate of this character wherein the construction thereof is novel in form and is conveniently operated, and when closed will be latched so as to prevent the accidental opening thereof.

25 A further object of the invention is the provision of a gate of this character which is simple in construction, thoroughly reliable and efficient in its purpose, readily and easily operated and inexpensive in manufacture and installation.

Other objects will be in part obvious and in part hereinafter set forth.

The invention accordingly consists in the features of construction, combination of elements and arrangement of parts which will be exemplified in the construction hereinafter described, and the scope of the application of which will be indicated in the appended claim.

40 In the accompanying drawings:

Figure 1 is an elevation of a gate constructed in accordance with the invention;

Fig. 2 is a side elevation showing by full lines the normal closed position of the gate 45 and by dotted lines the open position thereof;

Fig. 3 is a fragmentary sectional view on the line 3—3 of Fig. 1;

Fig. 4 is an enlarged fragmentary sectional view showing in detail the latch for the gate.

Similar reference characters indicate corresponding parts throughout the several views of the drawing.

55 Referring to the drawing in detail, A designates a pair of spaced vertically disposed

posts which are suitably anchored within the ground at opposite sides of the roadway, and these posts are of the required length so that a vehicle can travel therebetween 60 and beneath the axis of movement of the gate hereinafter fully described.

Journalled in the posts A near the upper end thereof is a horizontal pivot 5 which constitutes the axis of movement of the gate 65 and supports the same. The gate comprises spaced parallel side bars 6 and cross slats 7 which are fastened in any suitable manner to the side bars 6 at the desired intervals apart with respect to each other. The side 70 bars 6 are swingingly connected to the pivot 5 intermediate the ends thereof, so that the gate will swing vertically in the opening and close the same.

Carried by the side bars 6 at one end of 75 the gate is an adjustable balancing member in the form of a board 8 which is adjustable toward and away from the axis of movement of said gate so as to regulate the balancing action thereof. This adjusting of the 80 board 8 is preferably effected by employing suitable fasteners 8' which are passed through the board and through one of the adjustable openings 9' formed from the bars 6 as indicated in Fig. 1.

85 Mounted on the post A at opposite sides thereof are stops 9 which are located at the point of the axis of movement of the gate and are adapted to be engaged by the cross member carried by said gate to limit the 90 swinging movement of the gate when rocked in either direction, yet the said gate can be swung to a substantially horizontal plane for the passage of a vehicle without interference therewith.

95 Formed in the cross slats 7 at the closing end of the gate is a suitable opening 10, while mounted adjacent thereto is a leaf spring 11 which is secured at one end through the medium of fasteners 12, and one 100 end of this spring constitutes a latch tongue 13 which is adapted to engage in a notch 14 formed in a keeper 15 which is anchored in the roadway between the posts A, and when the latch member is in locking position it 105 fastens the gate closed.

Mounted above the pivot 5 are guide rollers 16 over which are trained in reverse directions releasing cables 17, the same being extended to suitable points at opposite 110 sides of the gate at the desired elevation in convenient reach of a driver within a vehi-

cle, and these cables 17 are trained through the opening 10 and connected to an eye 18 formed on the spring 11 so that on pulling upon either of the cables the latch member 11 will be raised for the unlatching of the gate so that it will swing to open position. After the vehicle has passed through the gate the same can be swung to closed position and the latch member 11 will, by its own gravity, engage with the keeper 15 for the latching of the gate.

From the foregoing description, taken in connection with the accompanying drawing, the construction and operation of the herein described gate will be readily apparent and, therefore, a more extended explanation has been omitted.

Having thus described my invention, I claim:

20 The combination with spaced vertically disposed posts, of a pivot mounted in the posts transversely thereof, a gate frame

swingingly supported for vertical movement upon the pivot, an adjustable balancing board carried by the upper end of the gate frame, a notched keeper mounted between the posts in a foundation, a spring latch member mounted on the gate frame and engageable in the notched keeper, a cross member connected to the sides of the gate frame above the pivot and extending beyond the sides of the gate frame, guides pendently supported on the cross member, cables connected with the latch member and trained over the guides in directions at opposite sides of the gate frame for swinging the gate frame, and laterally extending posts projecting from the front and rear faces of the vertically disposed posts and engageable by the extended ends of the cross member for limiting the swinging movement of the gate.

In testimony whereof I affix my signature.

GEORGE H. SHATTUCK.

Copies of this patent may be obtained for five cents each, by addressing the "Commissioner of Patents, Washington, D. C."
